UNITED STATES PATENT OFFICE.

JOHN KNAPE, OF GRAND RAPIDS, MICHIGAN.

ADJUSTABLE BRACKET.

1,008,720.

Specification of Letters Patent. Patented Nov. 14, 1911.

Application filed November 14, 1910. Serial No. 592,277.

To all whom it may concern:

Be it known that I, JOHN KNAPE, a citizen of the United States of America, residing at Grand Rapids, in the county of Kent and State of Michigan, have invented certain new and useful Improvements in Adjustable Brackets; and I do hereby declare the following to be a full, clear, and exact description of the invention, such as will enable others skilled in the art to which it appertains to make and use the same.

My invention relates to improvements in adjustable brackets, and its object is to provide a simple, cheap, and effective device having various novel features, hereinafter more fully described and particularly pointed out in the claims.

My improved bracket consists essentially of a channel bar adapted to be fixed in up-right position and provided with openings at regular intervals, said openings being substantially rectangular; a supporting member consisting of a flat bar arranged horizontal and projecting at right angles to the channel bar provided at its inner end with shoulders to engage the face of the channel bar, and a narrower upturned end to project through the upper part of one of the said openings and engage the inner surface of the channel bar; an inclined resilient brace bar secured to the horizontal bar at its outer end and having its inner end provided with shoulders to engage the outer face of the channel bar; an inwardly projecting and downwardly turned end to extend through the lower part of one of said openings and engage the inner surface of the channel bar, and a slide on the brace bar to lock the same in place in the channel bar, as will more fully appear by reference to the accompanying drawing in which:

Figure 1 is a side elevation of a device embodying my invention; Fig. 2 a front elevation of the same; Fig. 3 a perspective of the bracket proper detached from the channel bar with a portion broken off and shown on an enlarged scale; Fig. 4 an enlarged detail showing an elevation of the inner side of the channel bar with a bracket attached thereto; Fig. 5 an enlarged detail showing a horizontal section on the line 5—5 of Fig. 4; Fig. 6 the same on the line 6—6 of Fig. 4; and Fig. 7 an enlarged detail in section.

Like numbers refer to like parts in all of the figures.

1 represents a channel bar preferably formed of sheet metal with its edges folded at right angles to the middle portion.

2 is a horizontally disposed flat strip of metal of substantially uniform width and having an upturned outer end 2^a to retain a shelf or other article thereon, as occasion may require. The inner end of this horizontal bar is reduced in width to form shoulders 7^a to engage the outer surface of the channel bar and extending inward through an opening 5 in the channel bar and thence turned upward as at 6^a to engage the inner surface of the same. When the bar 2 is horizontal, the upturned end 6^a and the shoulders 7^a oppositely engage the respective inner and outer surfaces of the channel bar and securely hold the bar 2 from detachment or longitudinal movement. The brace bar 3 is rigidly secured at its outer end by a rivet 4 to the underside of the bar 2 and is pressed into a depression 9 in the bar 2 as at 9^a to prevent turning about the rivet and also extends diagonally downward to the channel bar 1 and is of such length that when its inner end is engaged with one of the openings 5 therein, the bar 2 will be held horizontal by the brace bar. The inner end of this brace bar is reduced in width forming shoulders 7 to engage the outer surface of the channel bar and extends inward through one of the openings 5 and thence downward and engages the inner surface of the channel bar. The downward extension 6 is short enough so that when the brace bar is sprung upward close to the upper side of the opening 5, this extension will pass freely through the opening, and the resilience of the brace bar 3 is such that it will be yieldingly held engaged with the bottom of the opening, and thus will not ordinarily become detached except when manually sprung toward the bar 2. To further secure the bracket in place, it is effectually locked by a slide 8 on the brace bar having a projection which enters the upper part of an opening 5, and prevents raising the lower end of the brace bar. This slide will move to place and lock the device automatically by gravity and is manually moved upon the brace bar to release the same, as occasion arises.

To increase the rigidity of the brace bar 3, I prefer to twist the same near the respective ends to turn the middle portion 3 to a vertical plane leaving the end portions 3^a

and 3^b in planes substantially at right angles to the plane of the middle portion, the portion 3^b furnishing the necessary resiliency. I also prefer to make the openings 5 5 wider in the upper part to receive the extension 6^a and the lower part of the opening 5 narrower and the extension 6 narrower than the extension 6^a, whereby shoulders are formed in the opening 5 to support the inner 10 end of the bar 2 and prevent it from moving down under the load thereon, whereby the extension 6^a can be made short and there will be but little, if any, vertical movement to the bar 2 in the opening.

15 The device is readily attached or detached by first moving the slide 8 up on the brace bar, then springing the bars 2 and 3 toward each other sufficient to permit the projection 6 to pass through the opening 5, then turning the bracket upward to bring the extension 6^a substantially horizontal when it can be removed through the opening 5. Obviously reversing the operation, will serve to attach the bracket to the channel bar.

20 25 This structure is very cheap and easy of construction, being easily made of sheet metal requiring but a single rivet and very little die work, and is also strong and reliable in operation.

What I claim is:—

1. An adjustable bracket, comprising a vertically disposed channel bar having rectangular recesses at intervals, said recesses having narrower lower portions forming shoulders in the recesses, a supporting bar having its end reduced to enter the wider part of said openings and its end turned upward, a brace bar attached to the supporting bar at the outer end and having its inner end reduced to enter the narrower portion of said openings and said end turned downward, said supporting bar also being supported on said shoulders and said brace bar resting in the lower part of an opening.

2. A bracket, comprising a channel bar having openings at intervals, a supporting bar and a brace bar attached to each other and having ends adapted to enter said openings and engage the inner surface of the channel bar, and a slide on the brace bar having a lug adapted to enter an opening and lock the brace bar therein.

In testimony whereof I affix my signature in presence of two witnesses.

JOHN KNAPE.
